(57) **CLAIM**

The ornamental design for a ski pole, as shown and described.

DESCRIPTION

FIG. 1 is a front perspective view of a ski pole showing my new design.

FIG. 2 is a rear view thereof.

FIG. 3 is a front view thereof.

FIG. 4 is a right side view thereof.

FIG. 5 is a left side view thereof.

FIG. 6 is a top view thereof.

FIG. 7 is a bottom view thereof; and,

FIG. 8 is an enlarged view of a subsection of FIG. 2 showing ornamental elements on the shaft of the ski pole.

The broken lines in the drawings form no part of the claimed design.

1 Claim, 2 Drawing Sheets(56)
